UNITED STATES PATENT OFFICE

HUBERT M. GRAY, OF TOLEDO, OHIO, ASSIGNOR OF ONE-HALF TO CHARLES I. HYLAND,
OF TOLEDO, OHIO

LOCOMOTIVE-CAB CURTAIN

Application filed May 13, 1929. Serial No. 362,599.

This invention relates to a curtain for use in connection with locomotive cabs for the purpose of closing the cab and protecting the occupants from the weather.

5 An object of the invention is to provide a locomotive cab curtain which can be readily and conveniently pushed or moved out of the way, but which is normally securely held in place to provide an adequate 10 closure for the cab.

Another object of the invention is to provide a locomotive cab curtain which is prevented from flapping due to the wind, but is sufficiently flexible to provide for egress 15 and ingress of persons to the cab.

Further objects of the invention will appear as the description proceeds, and the invention resides in the combination and arrangement of parts and the details of construction hereinafter described and claimed, 20 it being understood that changes in the precise embodiment of the invention herein disclosed can be made within the scope of what is claimed without departing from the spirit 25 of the invention.

The invention is shown by way of illustration in the accompanying drawings, in which:

Fig. 1 is a sectional elevation on the line 30 1—1 of Fig. 3 showing a side elevation of a portion of the cab with the curtain in place;

Fig. 2 is a transverse section on the line 2—2 of Fig. 1;

Fig. 3 is a section on the line 3—3 of Fig. 35 2; and

Fig. 4 is a sectional view on the line 4—4 of Fig. 1.

The illustrated embodiment of the invention comprises a locomotive cab 1 of the usual construction having a roof 2, and a substantially U-shaped hood 3 depending from the rear end portion of the roof. Disposed within the lower portion of the hood 3 is a substantially U-shaped rod 4, providing a support for the cab curtain 5. In this instance the cab curtain 5 is of fabric such as heavy canvas, and consists of two parts, 5^a and 5^b, which are connected by hook fasteners 6 at the rear of the cab. The curtain 5 is suspended from the support 4 by a

series of rings 8, which permit of sliding the curtain when desired to provide the proper opening, or to move the curtain parts to one side out of the way.

In order to prevent flapping of the curtains a plurality of elongate pockets 9 are provided longitudinally of the curtain to receive stiffening rods 10, which are coiled at 11 about the supporting rod 4 with the upper ends 12 projecting above the rod 4 and engageable with the inside of the hood 3. It will be apparent that the spring ends of the rods 9 serve to hold the curtain 5 in the proper position and eliminate flapping due to high winds, although the spring ends 65 allow the curtain to yield inwardly, but are adapted to return to normal position after the pressure has been relieved.

The opposite sides of the curtain 5 are held securely in place against the cab structure or suitable support to provide a substantially weatherproof connection with the inside of the cab structure, but the arrangement is such that these sides may be quickly and conveniently released in the event of impending accident, or any other exigency necessitating or requiring that the occupants of the cab leave the cab with the utmost haste. It is apparent that with the sides of the curtain permanently connected 80 to the cab structure, it would involve considerable delay to unfasten the curtain parts to enable the engineer and fireman to leave the cab quickly, but by providing a simple, releasable connection between the curtain 85 side and cab, which may be readily manipulated to free the curtain from its anchor, a generous opening is provided through which departure may be readily made, such opening being also usable for the main entrance 90 and exit for the cab in addition to being a safety feature.

As shown, attached to an inturned wall 13 of the cab is a substantially L-shaped upright member 14, which is provided with lips 15 facing inwardly in a direction parallel to the plane of the wall 13. The upright 14, lips 15, and wall 13 cooperate to provide a seat to receive one of the binding strips 16 between which is attached a side 100

edge portion of the curtain 5, as shown in Fig. 4. As shown in the drawings, a pair of recesses 17 are formed in the inner strip 16 to receive leaf springs 18. These springs normally tend to urge the stiffening strips 16 away from the seat, and are sufficient to force the strips clear from the lips 15.

For holding the binding members 16 in seating relation, an eccentric 19 is mounted at 20 to a bracket 21, and is provided with a handle 22. When the eccentric 19 is in the position shown in Fig. 2, it bears against the outer binding strip 16, and securely retains the members in seated relation, but upon swinging the handle 22 upwardly the strips 16 are released allowing the springs 18 to snap the strips out of seated relation and away from the lips 15, so that the curtain may be quickly shoved to one side. As shown the eccentric or cam 19 is not entirely curved at its periphery, but a portion is flattened to permit the binding strips to be abruptly snapped from seated relation by the springs 18 when the cam is released. As shown, similar connections are provided on opposite sides of the curtain so that both sides of the curtain may be detached in the above described manner.

It is to be understood that the above description is given by way of illustration and not of limitation, and numerous changes in details of construction, arrangement and operation may be effected without departing from the spirit of the invention, especially as defined in the appended claims.

What I claim as new and desire to secure by Letters Patent is:

1. The combination with a locomotive cab or the like, of a curtain, means for slidably supporting the top of the curtain, strips attached to opposite sides of the curtain, seats in the locomotive cab structure to receive said strips, spring means normally urging said strips out of said seats, and retaining members holding said strips in seated relation.

2. The combination with a locomotive cab or the like, of a curtain, a support for the top of the curtain, means for slidably attaching said curtain to said support, and means for releasably retaining one side of said curtain in place, said means including a holder member, and spring means tending to urge said curtain from engagement.

3. The combination with a locomotive cab or the like of a two-piece curtain, supporting means for the top portions of said curtain, means for releasably connecting the adjacent portions of the curtain, and releasable means holding one side of said curtain in place, said releasable means including a manually operable member movable to free the side of the curtain from engagement.

4. The combination with a locomotive cab or the like, of a curtain, including retaining means for one side of said curtain, a seat for said retaining means, means to hold said retaining means in said seat, and spring means for urging said retaining means from said seat upon release of said holding means.

5. The combination with a locomotive cab or the like, of a curtain, including a member attached to one side of said curtain, a seat for said member, means normally retaining said member in seated relation, and spring means adapted to be compressed by said retaining means when said member is disposed in seated relation, and operable abruptly to force said member from seated relation upon release of said retaining means, thereby to permit said curtain member to be moved free from engagement.

6. In combination, a locomotive cab, a substantially U-shaped support in the rearward portion of said cab, a curtain suspended from said support, a stiffening rod disposed longitudinally of said curtain to prevent flapping thereof, a spring on the upper end portion of said rod, and a part of said cab providing an abutment for said spring, thereby to permit inward swinging movement of said curtain against the tension of said spring.

7. In combination, a locomotive cab provided with a depending hood, a curtain support disposed with said hood, a curtain suspended from said support, stiffening rods for said curtain having a portion coiled about said support, and an extension on the upper end of each rod engageable with said hood.

8. In a locomotive cab, the combination of a curtain support, a curtain suspended from said support, stiffening members for said curtain for holding the same in position, means for yieldingly holding said members against swinging movement inside the cab, means to detachably hold the sides of said curtain in place, said holding means, including a seat in the cab structure, a member on the curtain engageable in said seat, and an operative member for forcing and retaining said member in said seat.

9. In a locomotive cab, a curtain support, a curtain suspended from said support, binding members on the opposite sides of said curtain, and means to retain said members in place against a cab portion, said means including a single operating lever for each side, and spring means for forcing the curtain out of retention when said lever is moved to a predetermined position.

10. In a locomotive cab, a curtain support, a curtain suspended from said support, binding members for opposite sides of the curtain, a seat for said binding members disposed on opposite side portions of the cab, cam means for holding each mem-

ber in its seat, and means to eject a member from its seat upon release of said cam means, thereby to free the curtain from attachment.

5 11. In a locomotive cab, a curtain support, a curtain suspended from said support, binding members for opposite sides of the curtain, and a manually operable cam member for each pair of binding members to hold the same in place whereupon release of said cam member on each side frees the curtain from engagement and provides an opening for the occupants of the cab to pass.

10 12. In a locomotive cab, a curtain support, a curtain suspended from said support, and completely enclosing the rear end of the cab, means for securing opposite sides of the curtain in place, said means including a single operating member for each side 20 which, upon manipulation in a predetermined manner, frees the respective side from engagement, thereby to afford an exit opening for the occupants of the cab.

15 13. In a locomotive cab, a curtain for enclosing a portion thereof, a support for the top portion of said curtain, an abutment for a side portion of said curtain, means cooperating with said abutment for clamping said curtain therebetween thereby to retain 30 same in position, and manually operated means for actuating said clamping means to release said curtain.

25 14. In a locomotive cab, a curtain, support for the top portion of said curtain, 35 abutment means adjacent a side of said curtain, and manually operated cam lever means cooperating with said abutment means to clamp said curtain therebetween.

30 15. The combination with a locomotive cab 40 structure of a curtain for enclosing a portion thereof, a support for the top of the curtain, and manually controlled lever means for releasably holding a side of said curtain in place against the cab structure.

45 16. In a locomotive cab, a curtain for enclosing a portion thereof, means to suspend 50 said curtain in a vertical position, and means for releasably retaining each longitudinal side edge portion of said curtain in place, said means comprising a pair of members for each side of the curtain for clamping the same in place, one of said members 55 consisting of a manually operated cam which upon actuation in one direction releases the curtain from clamping engagement.

In testimony whereof I have hereunto signed my name to this specification.

HUBERT M. GRAY.
